UNITED STATES PATENT OFFICE.

ARTHUR BESSEY SMITH, OF EVANSTON, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed April 7, 1922, Serial No. 550,451. Renewed August 16, 1926.

The present invention relates to multi-office telephone systems, but is concerned more particularly with multi-office telephone systems in which calls are completed through the medium of automatic switches; and the principal object is the provision of a system of the above character in which office names or numbers may be chosen without regard to the trunk routes required to reach the offices to which they are assigned.

Another object is to permit an office forming part of a Strowger trunking system, which is a system in which the office names or numbers are related to geographical districts, to be associated with a different district without changing its name or number, and consequently to permit a name of number which, according to the Strowger plan would be assigned to an office in one geographical district, to be assigned to an office in a different geographical district. The foregoing objects are accomplished by providing new and improved trunking arrangements for multi-office systems, whereby one or more routes toward a called subscriber may be employed tentatively and the proper route definitely chosen subsequently.

Another object is the production of a new device which will be called hereinafter a universal switcher.

Other objects which have to do with the detailed workings of a complete system will be pointed out and explained fully hereinafter, reference being had to the accompanying drawings comprising Figs. 1-11, inclusive, in which Figs. 1-7, inclusive, show by means of the usual circuit diagrams a sufficient amount of the apparatus in a system embodying the principles of the invention to enable the same to be understood; Fig. 8 is a map showing a section of the territory in which the system is located; Fig. 9 is a trunking diagram showing how calls may be trunked between certain of the offices shown in Fig. 8; Fig. 10 is a layout of certain of the sheets of drawings showing how Figs. 1-7, inclusive, join together; and Fig. 11 shows the front part of a calling device with which each subscriber's telephone in the system is to be equipped.

Of the equipment shown in Figs. 1-7, inclusive, the equipment shown in Figs. 1 and 2 is assumed to be located in the 6000 branch of Akard, Figs. 8 and 9; the equip-

ment shown in Figs. 3, 4 and 5, is assumed to be in Akard; the equipment shown in Fig. 6, is assumed to be in Ghent; and the equipment shown in Fig. 7 is assumed to be in Main.

The automatic substations A-A², inclusive, Fig. 9, of which the substations A and A² are shown by means of the usual circuit diagrams, Figs. 1 and 7, respectively, are substations of the usual automatic type, having the usual talking, signalling, and switch controlling instrumentalities.

The individual line switches associated with the substations are of the well-known rotary type in which the wipers have no normal position and move in a forward direction only. The circuits of the line switches C and C² are shown in full in Figs. 1 and 7, respectively, and will be described fully hereinafter.

The universal switcher US, Figs. 1 and 9, comprises the group of relays shown and a recording device, which device mechanically is a so-called minor switch. This minor switch is of a well-known and simple construction, having a single wiper which is operated step by step by an operating magnet to pick out a particular bank contact, and is restored to normal position by the release magnet 91. The universal switchers US' and US² are substantially the same as the universal switcher US, but differ in detail as will be explained fully hereinafter. The circuits of each of these universal switchers are shown in full and will be described fully hereinafter.

The rotary secondary switches D-D¹⁵, inclusive, are mechanically identical with either of the individual line switches, such as the line switch C, Fig. 1, but have their circuits altered slightly so as to prevent the switching relay from operating prematurely, when the release trunk conductor is grounded before or at the same time that a bridge is closed across line conductors thereof, upon the switch being seized. The operation of these switches will be explained fully hereinafter.

The repeaters R-R⁹, inclusive, Fig. 9, of which the repeaters R-R², inclusive, R⁴, R⁵ and R⁹, are shown in Figs. 2, 5, and 6, may be of any suitable two wire type, and each, as shown, comprises a repeating coil and a line and a release relay. The circuits of the

repeaters shown in Figs. 2, 3, and 6, are shown in full and will be described hereinafter.

The selectors E and E', F—F², inclusive, 5 G—G², inclusive, H and H', H³—H⁴, inclusive, and I—I³, inclusive, Fig. 9, are mechanically of the well known vertical and rotary type and accordingly their bank contacts are arranged in horizontal rows or 10 levels. The circuits of all the selectors are identical with each other, with the exception that those which are permanently associated with an inter-office trunk do not have release trunk conductors, whereas the local selectors 15 have. The circuits of the selectors I and E, which are a local and an incoming selector, respectively, are shown in full in Figs. 2 and 3, and will be explained fully hereinafter.

The connectors J—J², inclusive, Fig. 9, are 20 mechanically identical with either of the selectors, but have circuits which differ from the selector circuits because of the different functions assigned to them. The circuits of the connector J are shown complete in Fig. 25 7, and will be described fully hereinafter. The connectors J' and J², it will be understood, are each identical with the connector J, with the usual exception that, since they 30 are incoming switches, their release trunk conductors are not carried back with the line conductors.

Referring now particularly to Fig. 8, which as before stated, shows a part of the territory which the present system covers, 35 the entire system is assumed to comprise approximately 200 offices, which are grouped together in groups of ten, making in all twenty groups. Each of these groups forms a complete network, there being direct trunks 40 from each office to every other office in the same group. Only a few of the trunks, however, are shown, the others being omitted to avoid complicating the drawing. In each of the main offices of the system, there are 45 installed first and second selectors, and trunks to each of the twenty groups of offices are accessible to the second selectors. The trunks from any office to any group of offices terminate in third or office selectors at the 50 nearest or one of the nearest offices in that group and from thence the incoming traffic merges with the inter-office traffic local to the group. For example, in Fig. 8, the group of trunks from Akard to the group of offices in which Ghent is located terminate, as 55 shown, at Ghent, which is the nearest office, and which is the switching center for that group of offices for calls coming from Akard. After a connection has been extended from 60 Akard to Ghent, the next turn of the calling device causes a third or office selector in Ghent to operate and pick out the desired office in the usual manner.

It may be stated at this time, that according to common practice for systems of this

size, the letters of the alphabet appear on the calling device (Fig. 11) and the offices are listed in the directory before the subscribers' numbers, for example, MAIn—4926. When a subscriber calls this number, Main is 70 reached by dialing the first three letters M—A—I, or the letters that are capitalized, and the subscriber's number which comprises four digits is called after the office has been selected. The various offices in the group in 75 which Ghent is located are reached through one common group of trunks by multiplying together the correct levels of the second selectors, as will be hereinafter explained. The one condition, however, is that the third 80 letter in the office name cannot be the same for any two offices in the same group nor can it be in the same hole in the calling device, which amounts to practically the same thing. When such a conflict arises, the two 85 conflicting offices occupy the same level in the third selector banks, and a separate group of trunks is required. The names of the offices in the district for which Ghent is the switching center have been chosen so that the third letter does not come in the same 90 hole of the calling device, shown in Fig. 11, for any two of them. In order to show more clearly which office names are numerically similar, the numerical equivalent of the first 95 three letters of each office is written in parentheses.

It will be noted that there are only seven offices shown in the group in which Ghent is located. There are three other office names 100 Macey, Topaz, and Mahope, however, which, according to their first three letters would ordinarily not have been assigned or if assigned, would have been assigned to offices in the Ghent district. It is assumed that these 105 names belonged to the offices to which they are assigned while the system was manually operated and that the subscribers would not readily consent to a change of the office names when the system was changed to automatic operation. That being the case, these 110 three office names remain unchanged, which means that Macey, Mahope, and Topaz, are a 115 remotely situated part of the group of offices in which Ghent is located. This condition 120 makes it necessary, when calling Main, to take a trunk to Topaz at the same time a trunk is selected to Ghent, because the first two letters, M—A, of Main are the first two letters of Mahope. When the next digit is 125 dialed one of the two inter-office trunks is freed, and the call is completed over the other. The same thing occurs when either Southern or Topaz is called, the first letter thereof appearing in the same hole on the calling device, Fig. 11, and the second letter O being common to the two.

When Macey is being called from Akard, the calling of the first two letters, M—A, results in a trunk to Topaz being seized and 130

also a trunk to Ghent. It is assumed, however, that Macey, which is much nearer Akard than Topaz is, is near enough, and that the traffic to it from Akard is heavy enough, to warrant a separate group of trunks to it from Akard. Consequently, upon the calling of the next letter C, the trunk to Ghent and also the trunk to Topaz is freed and a direct trunk is taken from Akard to Macey.

Another situation wherein the universal switcher is used to an advantage arises in connection with the completion of local calls in the 6000 branch of Akard, and in completing calls from the 6000 branch of Akard to the 9700 branch of Akard. If, when a call originates in the 6000 branch of Akard, the letters A, K and A of Akard are dialed and the first digit is 6, a universal switcher in the calling branch office operates to restore the trunk to Akard to common use and the call is completed through local switches. Similarly if the first three letters A, K, and A of Akard are called and the first two digits are 9 and 7, the trunk to Akard is freed and a direct trunk to the nearby 9700 branch is connected up and the call is completed thereover.

It will be understood that other and similar problems are connected with each of the other districts in the system and that there may or may not be branch offices associated with each office, and that the examples given are chosen merely as being typical ones.

Referring now particularly to Fig. 9, which is a trunking diagram showing how the problems presented in Fig. 8 are taken care of, the trunking will be explained a little more in detail. In order to facilitate the tracing of calls, the second, third, and fourth selectors are labeled with the numerical equivalents of the letters in the exchange names that must be dialed to extend a connection thereto, and the hundreds selectors and connectors are labeled with the digits that must be dialed, after the office is selected, to extend a connection thereto. Assuming, that the subscriber at substation A' in Akard desires to call the subscriber at substation A² in Main, the rotary line switch C' operates to pick out a first selector, the selector E' for example, upon the removal of the receiver at the substation A', and when the calling device is turned in accordance with the first letter M, which letter appears in the fifth hole of the calling device, Fig. 11, the said first selector E' raises its wipers to the fifth level and selects an idle trunk, the trunk extending to the selector F³ for example.

When the calling subscriber operates his calling device in accordance with the second letter A of the office name, which letter appears in the first hole of the calling device, the second selector F³ raises its wipers to

the first level and selects an idle universal switcher, the universal switcher US' for example. When this occurs, the universal switcher US' connects up the rotary secondary switches D⁶ and D⁸, whereupon they operate to select trunks to Topaz and to Ghent, respectively, the trunks extending by way of the repeaters R² and R⁴ for example.

Upon the calling device being turned in accordance with the third letter I, the office selector G' in Topaz and the office selector G² in Ghent raise their wipers to the first level and proceed to search for idle trunks. The first level of the selector G' in Topaz is dead, and accordingly its trunk selecting operation is of no avail at this time. The first level of the selector G² in Ghent is connected with rotary secondary switches which have access to trunks to Main and, assuming that the rotary secondary switch D¹⁴ is the one selected, the rotary switch D¹⁴ operates to select an idle trunk to Main, the trunk extending by way of the repeater R⁹ and terminating in the selector H⁶ for example.

In the universal switcher US' a digit recording device (not shown in this drawing) disconnects the rotary secondary switch D⁶, thereby freeing the trunk to Topaz. In response to the calling of the digits in the desired number, the selectors H⁶ and I³ and the connector J operate in the usual manner to extend the connection to the substation A².

Assuming now that the subscriber at substation A' desires to converse with a subscriber whose line terminates in the Topaz office, the line switch C' operates in the usual manner to find an idle first selector, the selector E' for example, when the receiver is removed at the calling substation, and when the calling device is turned in accordance with the first letter T, which letter appears in the seventh hole of the calling device, shown in Fig. 11, the selector E' raises its wipers to the seventh level and picks out an idle second selector, the selector F⁴ for example.

When the calling device is turned in accordance with the second letter O, the selector F⁴ raises its wipers to the tenth level and picks out an idle universal switcher, the universal switcher US² for example. When this occurs the rotary secondary switches, D⁹ and D¹⁰ are connected up, whereupon they seize trunks to Topaz and to Ghent, respectively, which trunks it will be assumed are the ones shown in the drawing.

When the calling device is turned in accordance with the third letter P, the selector G' and G² raise their wipers to the sixth level and rotate them in search of idle trunks. The trunk selecting operation of the selector G² in this case is of no avail,

the sixth level being dead. The selector G', however, picks out an idle selector, the selector H' for example.

In the universal switcher US², the digit recording device, upon operating in accordance with the third digit of the number, disconnects the rotary switch D¹⁰, whereupon the trunk to Ghent is freed.

The calling subscriber now operates his calling device in accordance with the remaining part of the number, whereupon the usual selectors and connectors are operated to extend the connection to the desired line in the usual manner.

15. It will be understood that if the calling subscriber had been, in the preceding example, calling a subscriber in Southern instead of Topaz, the switches G' and G² would have stepped up to the eighth level 20 and the universal switcher US² would have freed the trunk to Topaz instead of the trunk to Ghent.

Assuming now that the calling subscriber at substation A in the 6000 branch of Akard 25 desires to call some subscriber in the Akard office, he removes his receiver, whereupon the rotary line switch C picks out an idle universal switcher, the universal switcher US for example. When this occurs, the rotary 30 secondary switch D' associated with the universal switcher US' operates to pick out an idle trunk to Akard, the trunk extending by way of the repeater R' for example, there being no first selectors in the branch office. 35 The rotary switches D and D², however, are not connected up for the time being.

When the calling device is turned in accordance with the first letter A, which letter appears in the first hole in the calling 40 device, the first selector E in the Akard office raises its wipers to the first level and picks out an idle second selector, the selector F for example.

In response to the calling of the second 45 letter K, which letter appears in the fifth hole of the calling device, the second selector F raises its wipers to the fifth level and picks out an idle third selector, the third selector G for example, and in response to 50 the calling of the third letter A, the said third or office selector G raises its wipers to the first level, and picks out an idle fourth selector, the selector H for example.

If the next digit called is any digit except 55 6, the selector H, upon operating in response to the digit, seizes a local fifth selector. However, if the next digit is 6, the selector H raises its wipers to the sixth level 60 switch which has access to the 6000 branch of Akard, which is the branch in which the call originated, the rotary secondary switch D¹⁵ for example. When this occurs, however, the universal switcher US in the originating 65 branch office, having recorded the digits

dialed, disconnects the rotary switch D' and connects up the rotary secondary switch D², whereupon the trunk to Akard is freed; the switches in Akard are released; and the trunk from Akard back to the originating 70 branch office is freed. In response to the secondary switch D² being connected up, an idle selector is seized, the selector I' for example. The calling subscriber now calls the three remaining digits of the number 75 in the usual manner, whereupon the call is completed locally without tying up any inter-office trunks.

Assuming now, that the calling subscriber calls the digit 9 after having dialed the letters A, K and A, the connection is extended 80 to a local fifth selector, the selector I for example. If the next digit called is any digit other than 7, a local connector is seized and the calling of the remaining digits 85 extends the connection to the desired line in the usual manner. However, if the digit is 7, the wipers are raised to the seventh level, and an outgoing rotary secondary switch, the switch D¹¹ for example, is seized. That 90 being the case, the switch D¹¹ seizes a trunk to the 9700 branch of Akard, which is a branch office containing only 100 lines. When this occurs, however, the universal 95 switcher US, having recorded all the digits thus far dialed, disconnects the trunk to Akard, whereupon the connection established to Akard is released. The switcher US also connects up the rotary secondary switch D, whereupon a direct trunk from 100 the 6000 branch to the 9700 branch is seized and the connection is completed thereover in response to the calling of the two remaining digits in the desired number.

The apparatus, having been described 105 more or less in general, will now be described in connection with a detailed description, of its operation. For this purpose, it will be assumed that the subscriber at substation A, Figs. 1 and 9, desires to 110 converse with the subscriber at substation A², Figs. 7 and 9, and whose number is MAIn-9496.

When the receiver is removed at the substation A, a circuit is completed over line 115 conductors 2 and 3, for line relay 6, of the line switch C. Upon energizing, line relay 6 places ground upon private normal conductor 4 at armature 12, thereby making the calling line busy immediately in the banks 120 of the connectors which have access to it. The placing of ground upon private normal conductor 4 also closes a circuit for switching relay 5, and stepping magnet 10, in series. As a further result of the energization of line relay 6, it connects the test wiper 14 to a point in the circuit between stepping magnet 10, and switching relay 5, at armature 11. From this point the operation depends upon whether or not the trunk, upon 130

which the wipers are standing, is busy or idle. If the trunk is idle, there is no ground potential upon the test contact thereof and switching relay 5, energizes immediately, but if it is busy there is a ground potential upon the test contact thereof, and switching relay 5 is short circuited, and stepping magnet 10, which interrupts its own circuit, operates in the manner of a buzzer to advance its wipers step by step in search of an idle trunk. When an idle trunk is reached, which trunk it will be assumed is the one terminating in bank contacts 16—18, inclusive, switching relay 5, being no longer short circuited, energizes in series with rotary magnet 10. Rotary magnet 10, however, does not energize at this time, on account of the high resistance of switching relay 5. As a result of the energization of switching relay 5, armature 8 opens the test circuit and prepares the holding circuit, thereby placing ground upon test contact 17, which makes the seized trunk busy immediately. As a further result of the energization of switching relay 5, it disconnects the line conductors 2 and 3 from ground and from the winding of line relay 6; respectively, at armatures 7 and 9, and extends them by way of the working contacts of these armatures, wipers 13 and 15, bank contacts 16 and 18, and armatures 45 and 47 to the upper and lower windings of line relay 26 of the universal switcher US. Upon energizing over the calling subscriber's loop, line relay 26 closes a circuit for release relay 27 at armature 49. Release relay 27, upon energizing, prepares a locking circuit for relays 30—33, inclusive, at armature 50; prepares a circuit for operating magnet 90 at armature 51; and at armature 52 places ground upon release trunk conductor 20, thereby establishing the usual holding circuit for the line switch C, by way of bank contact 17, wiper 14, and armature 8 and its working contact, before the slow acting line relay 6 has had time to deenergize. As a further result of the energization of line relay 26, it closes a circuit for impulse relay 36 at armature 48. Impulse relay 36, upon energizing, closes a bridge across conductors 108 and 110, whereupon line relay 171 of the secondary switch D', upon energizing, places ground upon release trunk conductor 109 at armature 179; connects switching relay 170 in series with stepping magnet 172 at armature 178; and at armature 177 connects test wiper 181 to the above circuit at a point between switching relay 170 and stepping magnet 172. The switch now operates in the same manner as explained hereinbefore for the rotary line switch C to advance to wipers 180—182, inclusive, into engagement with an idle trunk, and assuming the trunk comprising conductors 183—185, inclusive, to be the first one found to be idle, switching relay 170, upon energizing, opens the test circuit and prepares the holding circuit at armature 175; places a shunt around armature 178 and working contact at armature 174; and at armatures 173 and 176 disconnects the incoming trunk conductors 108 and 110 from line relay 171 and from ground, respectively, and extends them by way of wipers 180 and 182, trunk conductors 183 and 185, and the left hand windings of the repeating coil of the repeater R', to the upper and lower windings of line relay 186 of the repeater R'. Line relay 186, upon energizing, closes a circuit for release relay 187 at armature 188, and release relay 187, upon energizing, places ground upon release trunk conductor 184, thereby establishing the usual holding circuit for switching relay 170 of the switch D'. As a further result of the energization of line relay 186 of the repeater R', it closes a bridge across the conductors 191 and 192 at armature 189, whereupon line relay 210 of the distant selector E in Akard energizes, thereby closing a circuit for release relay 211 at armature 220. Release relay 211, upon energizing, prepares a circuit for switching relay 214 at armature 221, and at armature 222 opens a point in the circuit of release magnet 215 and prepares a circuit for vertical magnet 219.

The calling subscriber now operates his calling device in accordance with the first letter M of the desired office, thereby producing five interruptions in the circuit of line relay 26 of the universal switcher US, Fig. 1. Each time line relay 26 deenergizes in response to one of these interruptions, it opens the circuit of impulse relay 36 at armature 48, and each time impulse relay 36 deenergizes, it opens the circuit of line relay 186 of the repeater R', and each time line relay 186 of the repeater R' deenergizes, it opens the circuit of line relay 210 of the selector E. Each time line relay 210 deenergizes in response to one of the five interruptions produced in its circuit, it closes the following circuit for vertical magnet 219: From ground by way of the resting contact of armature 228 and said armature, armature 220 and its resting contact, armature 222 and its working contact, relay 212, and vertical magnet 219 to battery. By the operation of vertical magnet 219, the shaft of the switch is raised five steps and carries the wipers 230—232, inclusive, opposite the fifth level of bank contacts. Relay 212 is energized in series with vertical magnet 219, and being slow acting retains its armature attracted throughout the vertical movement, and, upon the closing of off normal contacts 218 closes a circuit for stepping relay 213. Stepping relay 213, upon energizing, closes a locking circuit for itself at armature 224, and at armature 225 prepares a circuit for

rotary magnet 217. Upon the termination of the vertical movement, slow acting relay 212 deenergizes, thereby completing the circuit of rotary magnet 217. Rotary magnet 217, upon energizing, advances the wipers 230—232, inclusive, into engagement with the first set of bank contacts, at the same time opening the circuit of stepping relay 213 at interrupter contacts 233. Stepping relay 213, upon deenergizing, opens the circuit of rotary magnet 217, at armature 225, and rotary magnet 217 upon deenergizing closes its interrupter contacts 233 again.

From this point, the operation depends upon whether or not the trunk terminating in the first set of contacts is busy. If it is idle, switching relay 214 energizes immediately and, if it is busy, switching relay 214 is short circuited by the ground potential which is present on the test contact thereof, and stepping relay 213 energizes again, whereupon rotary magnet 217 energizes also, thereby advancing the wipers into engagement with the second set of bank contacts. This alternate operation of stepping relay 213 and rotary magnet 217 continues until an idle trunk is reached. When an idle trunk is reached, which trunk it will be assumed is the one extending to the selector F^3 , switching relay 214, being no longer short circuited, energizes in series with stepping relay 213; opens the test circuit and prepares the holding circuit at armature 227; disconnects ground from armature 220 of line relay 210 at armature 228; and at armatures 226 and 229 disconnects the incoming trunk conductors 191 and 192 from the windings of line relay 210 and extends them by way of wipers 230 and 233, the bank contacts with which these wipers are in engagement, and the associated trunk conductors to the upper and lower windings of the line relay (not shown) of the selector F^3 . When this occurs, the selector F^3 is prepared for operation in the usual manner in response to the energization of its line relay.

In the universal switches US, line relay 26, upon deenergizing in response to each of the interruptions produced in its circuit by the calling device at the calling substation, in addition to opening the circuit of impulse relay 36 at armature 48, closes the following circuit for stepping magnet 90: From ground by way of the resting contact of armature 46 and said armature, armature 49 and its resting contact, armature 51 and its working contact, relay 28, and stepping magnet 90 to battery. By the operation of the stepping magnet 90, which receives five impulses over this circuit, wiper 99 is advanced step by step until it comes to rest upon the fifth associated bank contact 95. Relay 28 is energized in series with stepping magnet 90 and, being slow acting, retains

its armature attracted throughout the series of impulses. At the end of the series of impulses, slow acting relay 28 deenergizes, thereby closing at armature 53 a circuit for release magnet 91, by way of off normal contacts 93. It will be noted that a branch of this circuit extends by way of armature 92 of release magnet 91 and its resting contact, lower winding of relay 29, and wiper 99, to bank contact 95. Relay 29, however, does not energize at this time for the reason that bank contact 95 is not connected up so as to complete the circuit. Release magnet 91, upon energizing in response to the closing of its circuit, closes the following circuit for seizing relay 35: From ground by way of the resting contact of armature 53 and said armature, off normal contacts 93, armature 92 and its working contact, resting contact of armature 55 and said armature, and the upper winding of relay 35 to battery. As a further result of the energization of release magnet 91, it restores the wiper 99 to normal, its own circuit, and the circuit of the upper winding of relay 35, being opened at off normal contacts 93 when the wiper 99 reaches normal position. As a result of the momentary closing of the circuit of the upper winding, which winding is of low resistance and efficient and consequently has a strong pull, armature 76, which is adjusted to operate easily and to operate before the other armatures have moved, is brought into engagement with its working contact, thereby locking the associated lower winding to release trunk conductor 20. Relay 35, upon energizing fully, extends release trunk conductor 20 through to release trunk conductor 109, of the secondary switch D' at armature 77; extends the trunk conductors 19 and 21, to trunk conductors 108 and 110 at armatures 74 and 78; and at armature 75 closes a circuit for cut off relay 25. Cut off relay 25, upon energizing, disconnects ground from armature 49 of line relay 26 at armature 46, and at armature 45 and 47 disconnects trunk conductors 19 and 21 from the windings of line relay 26. Line relay 26, upon deenergizing, opens the circuit of impulse relay 36 at armature 48, and impulse relay 36, upon deenergizing, removes the local bridge from across conductors 108 and 110 at armature 79, thereby leaving line relay 186 of the repeater R' under the direct control of the calling device at substation A. Release relay 27, upon deenergizing in response to the ground being removed from armature 49 of line relay 26 at armature 46 of relay 25, disconnects ground from release trunk conductor 20 at armature 52, leaving the said conductor grounded by way of the holding circuit which extends back from armature 190 of release relay 187 of the repeater R' .

The first letter in the desired number hav-

ing been dialed, the net result so far accomplished is that the selector E in the Akard office has raised its wipers to the fifth level and selected the selector F³, and, in the originating branch office, the universal switcher US has responded to the first letter and, since that letter determined definitely that the call is not intended for a subscriber that may be reached by way of one of the alternate paths, has definitely seized the trunk to Akard and has disconnected its own line relay and consequently will not respond to the calling of the remaining part of the number.

When the calling subscriber operates his calling device in accordance with the second letter A of the desired office, a single interruption is produced in the circuit of line relay 186, of the repeater R', which interruption is relayed by the line relay of the repeater R' to the line relay (not shown) of the selector F³, Fig. 3. The selector F³ now raises its wipers to the first level, rotates them, and picks out an idle trunk, which trunk it will be assumed is the one extending to the universal switcher US'. That being the case, line relay 244 of the universal switcher US', upon energizing in response to the seizure of the switcher by the selector F³, closes at armature 255 a circuit for release relay 245. Release relay 245, upon energizing, prepares a circuit for stepping magnet 247 at armature 257, and at armature 250 places ground upon release trunk conductor 241, thereby establishing the usual holding circuit for the switching relay (not shown) of the selector F³ and the switching relay 214 of the selector E. As a further result of the energization of the relay line 244, it closes at armature 254 a circuit for impulse relays 266 and 269 in multiple. Relay 266, upon energizing, closes a local bridge across the conductors 285 and 287 of the rotary secondary switch D⁸, whereupon line relay 302 energizes and the switch proceeds to select an idle trunk in the hereinbefore described manner. Assuming that the trunk extending to the repeater R² and comprising conductors 303-305, inclusive, to be the one selected, switching relay 301, upon energizing at the end of the trunk selecting operation, extends trunk conductors 285 and 287 to the line relay of the repeater R², and prepares the holding circuit. Line relay 315 of the repeater R², upon energizing in response to the seizure of the said repeater, closes a circuit for release relay 316 at armature 317. Relay 316, upon energizing, places ground upon release trunk conductor 304 at armature 319, thereby establishing the usual holding circuit for switching relay 301 of the switch D⁸. As a further result of the energization of line relay 315 of the repeater R², it closes a bridge across the conductors 325 and 326 at armature 318. When this occurs, the line and release relays (not shown) of

the selector G² in Ghent, energize, thereby preparing the switch for operation in the usual manner.

In the universal switcher US', impulse relay 269, upon energizing in multiple with impulse relay 266, closes a local bridge across conductors 291 and 293 at armature 284, whereupon the secondary switch D⁶ selects an idle trunk in the usual manner, which trunk it will be assumed is the one extending to the repeater R⁴. That being the case, the line and release relays of the repeater R⁴ energize, thereby closing a bridge across the associated out-going trunk conductors and establishing the usual holding circuit for the switching relay of the secondary switch D⁶. In response to the closing of the bridge across the conductors of the trunk outgoing from the repeater R⁴, the line and release relays of the associated incoming selector G' in Topaz, Fig. 9, energize, thereby preparing the switch for operation in the usual manner.

When the calling subscriber turns his calling device in accordance with the third letter I in the name of the desired office, one interruption is produced in the circuit of line relay 186 in the repeater R', and the said line relay 186, upon deenergizing in response to this interruption, produces an interruption in the circuit of line relay 244 of the universal switcher US'. Line relay 244, upon deenergizing, opens the circuit of impulse relays 266 and 269 at armature 254, whereupon these relays deenergize also, thereby momentarily opening the associated bridges at armatures 283 and 284. In response to the opening of the bridge across conductors 285 and 287, line relay 315 of the repeater R², deenergizes momentarily, thereby producing an interruption in the circuit of the line relay of the selector G² in Ghent. When this occurs, the selector G² raises its wipers to the first level and rotates them in search of an idle trunk. Assuming the trunk extending to the secondary switch D¹⁴ to be the one selected by the selector G², the said switch D¹⁴ operates in the usual manner to select an idle trunk, which trunk it will be assumed is the one extending to the repeater R⁹. That being the case, the line and release relays of the repeater R⁹ energize, the former closing a bridge across the conductors of the associated inter-office trunk, which extends to Main, and the latter establishing the usual holding circuit for the switches D¹⁴ and G². In response to the closing of the bridge across the conductors of the inter-office trunk, the line and release relays of the incoming selector H⁶ Fig. 7, which selector is in Main, Fig. 9, energize, thereby preparing the switch for operation in the usual manner.

By identical operation, the momentary deenergization of impulse relay 269 of the universal switcher US', Fig. 3, produces a

momentary interruption in the circuit of the line relay of repeater R^4 , which relay in turn repeats the interruption to the line relay of the associated selector G' in Topaz, Fig. 9. 5 When this occurs, the selector G' raises its wipers to the first level and rotates them in search of an idle trunk. It will be noted, however, that the first level of the selector G' is dead and, consequently, the trunk 10 selecting operation of the said selector G' does not perform any useful function at this time.

In the universal switcher US' , line relay 244, upon deenergizing in response to the 15 previously mentioned momentary interruption produced in its circuit, not only opens the circuit of impulse relays 266 and 269, as explained, but also closes the following circuit for stepping magnet 247: From ground by way of resting contact of armature 253 and said armature, armature 255 and its resting contact, armature 257 and its working contact, relay 246, and stepping magnet 247 to battery. By the operation 20 of stepping magnet 247, which receives a single impulse at this time, wiper 249 is advanced into engagement with the first bank contact 259. Slow acting relay 246 is energized in series with stepping magnet 247 and retains its armature attracted while the wiper is being advanced. Upon the termination of the impulse, slow acting relay 246 deenergizes, thereby closing at armature 258 the circuit of release magnet 248, by way of 25 off normal contacts 250, which contacts became closed when wiper 249 moved from its normal position. Release magnet 248, which has a comparatively heavy armature and also a stiff spring adjustment, is not able to energize immediately and hesitates a small fraction of a second. It will be noted that a branch of the circuit of release magnet 248 extends by way of armature 262 of release magnet 248 and its resting contact, wiper 249, the first associated bank contact 259, and seizing relay 265 to battery. Release magnet 248, upon energizing, disconnects wiper 249 at armature 262, and restores it to normal, its circuit being opened 30 at off normal contacts 250 when wiper 249 reaches normal position. The time that elapses, between the closing of the circuit of release magnet 248 and the circuit of relay 265 in multiple and the energization of release magnet 248, is ample to allow armature 272 of relay 265, which armature has weak spring tension and is adjusted to operate before the other armatures do, to be brought into engagement with its working contact, thereby closing a locking circuit for relay 265. Relay 265, upon energizing fully, connects the release trunk conductor 241 through to release trunk conductor 286 of the secondary switch D^8 at armature 234, and at armatures 270 and 273 extends trunk conductors 240 and 242 to the trunk conductors 285 and 287 of the switch D^8 . As a further result of the energization of seizing relay 265, it closes a circuit for cut off relay 243 at armature 271. Cut off relay 243, 70 upon energizing, removes ground from armature 255 of line relay 244 at armature 253, thereby opening the circuit of release relay 245, and at armatures 251 and 252 disconnects line relay 244 from line conductors 240 and 242. Line relay 244, upon deenergizing, opens the circuit of impulse relays 266 and 269 at armature 254. Impulse relay 266, upon deenergizing, removes the local bridge from across trunk conductors 285 and 287 at armature 283, thereby leaving the line relay 315 of the repeater R^2 under the direct control of line relay 186 of the repeater R' , Fig. 2. Impulse relay 269 of the universal switcher US' , upon deenergizing in response to the deenergization of line relay 244, removes the local bridge from across conductors 291 and 293 at armature 284, whereupon the connection to Topaz is released and the repeater R^4 and associated trunk reverts to common use in the usual manner.

Release relay 245, of the universal switcher US' , upon deenergizing in response to the energization of cut-off relay 243, removes ground from release trunk conductor 241 at armature 250, leaving the said conductor grounded by way of the holding circuit which extends back from armature 219 of release relay 316 of the repeater R^2 , 90 Fig. 5.

The calling subscriber now turns his calling device in accordance with the first digit 9 in the desired number, whereupon nine interruptions are produced in the circuit of the line relay of the repeater R' and are relayed to the repeater R^2 and from thence to the incoming selector H^6 , Fig. 7, by way of the repeater R^9 , Fig. 6. In response to the nine interruptions produced in the circuit of its line relay, the selector H^6 raises its wipers to the ninth level, and rotates them in search of an idle trunk. Assuming that the trunk extending to the hundreds selector I^3 is the first one found to be idle and consequently 105 the one selected, the line and release relays (not shown) energize, thereby establishing the usual holding circuit for the selector H^6 .

In response to the calling of the next digit 4 in the desired number, the selector I^3 raises 120 its wipers to the fourth level and rotates them in search of an idle connector. Assuming the connector J to be the first one found to be idle, line relay 501 energizes in response to the seizure of the switch by the selector I^3 , and closes a circuit for release relay 503 at armature 514. Release relay 503, upon energizing, opens a point in the circuit of the release magnet 509 and prepares a circuit for vertical magnet 509 at 130

armature 517; places ground upon armature 522 of busy relay 506 at armature 516; and at armature 515 places ground upon release trunk conductor 498, thereby establishing the usual holding circuit for the selectors H^e and I^e.

The calling subscriber now operates his calling device in accordance with the next digit 9 in the desired number, whereupon 10 nine interruptions are produced in the circuit of line relay 501 of the connector J. Each time line relay 501 deenergizes in response to one of these interruptions, it sends an impulse of current to vertical magnet 509, the first impulse being delivered over the following circuit: From ground by way of armature 514 and its resting contact, armature 517 and its working contact, resting contact of off normal spring 513 and 20 said spring, relay 504, and vertical magnet 509 to battery. By the operation of vertical magnet 509, which receives nine impulses of current at this time, the shaft and wipers of the connector J are raised step by step until 25 the latter come to rest opposite the ninth level of bank contacts, which level is the one in which the line of substation A² terminates. Relay 504 is energized in series with vertical magnet 509, and being 30 slow acting retains its armature attracted throughout the vertical movement, thereby maintaining its own circuit and that of vertical magnet 509, at armature 518, intact after the off normal springs have shifted, 35 as they do upon the first vertical step. At the end of the vertical movement, slow acting relay 505 deenergizes, and transfers the impulse circuit from vertical magnet 509, to rotary magnet 511.

The calling subscriber now operates his calling device in accordance with the digit six, which is the next and last digit in the desired number, whereupon six interruptions 40 are produced in the circuit of line relay 501. Each time line relay 501 deenergizes in response to one of these interruptions, it closes a circuit for rotary magnet 511 as follows: From ground by way of armature 514 and its resting contact, armature 517 and its 45 working contact, normally open contacts controlled by off normal spring 513, armature 518 and its resting contact, resting contact of armature 523 and said armature, armature 530 and its resting contact, and rotary magnet 511 to battery. By the operation 50 of rotary magnet 511, the switch wipers 532-534, inclusive, are rotated step by step until they come in engagement with bank contacts 535-537, inclusive. Relay 507 is energized in multiple with rotary magnet 511 and, being slow acting, retains its armature attracted throughout the rotary movement. Upon energizing, relay 507 disconnects test wiper 533 from switching relay 508 and connects it with busy relay 506, and

at armature 526 places a shunt around armature 523 and its resting contact, so as to maintain its own circuit and that of rotary magnet 511 intact, in case busy relay 506 energizes while test wiper 533 is passing over 70 busy contacts.

Assuming first that the line of substation A² is busy, in which case there is a ground potential upon test contact 536, busy relay 506 is energized at the end of the rotary 75 movement and slow acting relay 507, upon deenergizing, completes the following locking circuit for busy relay 506: From ground by way of armature 516 and its working contact, armature 522 and its working contact, 80 normally closed contacts controlled by armature 525, and busy relay 506 to battery. In this case, armature 523 of busy relay 506 having been operated, as a further result of the deenergization of slow acting relay 507, it disconnects itself and rotary magnet 511 from the impulse circuit at armature 526. The switching relay 506 cannot energize, even though the calling line should become idle, and busy relay 506, being locked 85 through a local circuit, cannot deenergize as long as release relay 503 is energized. As a further result of the energization of busy relay 506, it connects at armature 524 a lead from the right hand winding of the transformer associated with the busy machine T with the lower talking conductor, thereby sending back a busy tone to the calling subscriber, which tone informs him that he cannot obtain the desired connection for the 90 time being. The subscriber, upon hearing this busy tone, replaces his receiver, whereupon the connection is released in the usual manner.

Assuming now that the line of substation A² is idle when the wipers of the connector J arrive upon the bank contacts 535-537, inclusive, in which case there is no ground potential upon test contact 536 and busy relay 506 is not energized, slow acting relay 507, upon deenergizing upon the cessation of the operating impulses, closes at armature 525 the following circuit for switching relay 508 and switching relay 538, of the connector J and the line switch C², respectively, in 100 series: From ground by way of armature 516 and its working contact, armature 522 and its resting contact, upper winding of switching relay 508, resting contact of armature 525 and said armature, test wiper 533, bank contact 536, switching relay 538, and stepping magnet 539 to battery. Switching relays 538 and 508 energize in series over this circuit. Stepping magnet 539, however, 105 does not energize on account of the high resistance of relay 538. Relay 538, upon energizing, clears the called line of its normal battery and ground connections, but owing to an interlocking device (not shown) between its armature, and that of line relay 110

540, the armature of relay 538 operates only about half way and consequently the associated wipers are not connected up.

In the connector J, relay 508, upon energizing, closes a locking circuit for itself at the lightly adjusted armature 529, which armature is adjusted so as to operate first; disconnects rotary magnet 511 and relay 507 from the impulse circuit at armature 530 so that any further operation of the calling device will be ineffective in operating rotary magnet 511; places direct ground on test wiper 533 at armature 528; and at armatures 527 and 531 connects up the line wipers 532 and 534, whereupon ringing current from the interrupted generator lead is projected out over the called line returning by way of the upper winding of ring cut off relay 505. This ringing current operates the called subscriber's bell intermittently in the usual manner.

When the called subscriber responds to the ringing of his bell by removing his receiver, a direct current bridge is placed across the conductors of his line, whereupon ring cut off relay 505 in the connector J, energizes and closes a locking circuit for its lower winding at the lightly adjusted armature 520, which armature is adjusted to close before armatures 519 and 521 break away from their resting contacts. Upon fully energizing, ring cut off relay 505 connects the called line to the upper and lower windings of the battery feed impedance 502.

35 The calling and called subscribers may now converse with each other in the usual manner, the talking circuit being outlined by the heavy conductors. Talking battery is supplied to transmitter of the calling substation from the line relay of the repeater R', Fig. 2, and to the transmitter of the called substation from battery feed impedance 502 of the connector J, Fig. 7.

45 After the conversation is completed, the two subscribers replace their receivers. When the receiver is replaced at substation A, the circuit of line relay 186 of the repeater R' is opened, and the said relay upon deenergizing, opens the circuit of release relay 187 at armature 188, and at armature 189 opens the circuit of line relay 315 of the repeater R', Fig. 5. Line relay 315 of the repeater R', upon deenergizing, opens the circuit of release relay 316 at armature 317, and at armature 318 opens the circuit of the line relay of the repeater R', Fig. 6. The line relay of the repeater R', upon deenergizing, opens the circuit of the associated release relay at its upper armature, and at its lower armature opens the circuit of line relay 501 of the connector J. Line relay 501, upon deenergizing opens the circuit of release relay 503.

60 Returning now to the repeater R', Fig. 2, release relay 187, upon deenergizing removes

ground from release trunk conductor 184, whereupon switching relay 170 of the secondary switch D', seizing relay 35 of the universal switcher US, cut off relay 25 of the same switcher, and switching relay 5 of the line switch C deenergize. This restores conditions in the line switch C to normal and renders the universal switcher US, the secondary switch D', and the repeater R' accessible for common use.

75 In the repeater R', Fig. 5, release relay 516 upon deenergizing, removes ground from release trunk conductor 304, at armature 319, whereupon relay 301 of the secondary switch D^s, seizing relay 265 and cut off relay 243 of the universal switcher US', the switching relay (not shown) of the selector F^s, and the switching relay 214 of the selector E deenergize. When this occurs, conditions in the secondary switch D^s, and the universal switcher US' are restored to normal. In the selectors E and F^s, the respective release magnets energize and restore the switches to normal, the circuit of release magnet 215 of the selector E being as follows: From ground by way of the resting contact of armature 228 of switching relay 214 and said armature, armature 220 and its resting contact, armature 222 and its resting contact, off normal contacts 216, and release magnet 215 to battery. When release magnet 215 energizes, the shaft and wipers of the switch are restored to normal position in the usual manner, the circuit of release magnet 215 being opened at off normal contacts 216 by the switch shaft when the latter reaches normal position.

95 In response to the deenergization of the release relay of the repeater R', Fig. 6, the ground potential is removed from associated release trunk conductor, whereupon the switching relay of the switch D¹⁴, and the switching relay (not shown) of the selector G^s, deenergize. When this occurs, the wipers of the selector G^s are restored to normal position in the usual manner.

110 In the connector J, release relay 503, upon deenergizing in response to the opening of its circuit by the deenergization of the line relay 501, removes ground from armature 522 at armature 516; removes ground from release trunk conductor 498 at armature 415, whereupon switching relay 508, ring cut off relay 505, and the switching relays (not shown) of the selectors H^s and I^s, deenergize. In response to the deenergization of switching relay 503, the busy potential is removed from the test contact of the called line at armature 528, and in response to the deenergization of the switching relays of the selectors H^s and I^s, the two selectors are restored to normal position by the operation of their respective release magnets in the usual manner. As a further result of the deenergization of release relay 503 of

the connector J, the following circuit is closed for release magnet 510: from ground by way of armature 514 and its resting contact, armature 517 and its resting contact, off normal contacts 512, and release magnet 510 to battery. Release magnet 510, upon energizing, allows the shaft and wipers to restore to normal position in the usual manner, its circuits being opened at off normal contacts 512, by the shaft when the latter reaches normal position. The entire connection is now released and all the common apparatus used therein is restored to common use.

15 It will be assumed now, that the subscriber at substation A, Fig. 1, desires to converse with some subscriber in the office of Mahope, of which the first two letters M and A coincide with the first two letters of
20 Main, but which, due to reasons herein-before given, is not reached through the same switching center as Main. That being the case, the calling subscriber at substation A, after having removed his receiver,
25 dials the first two letters M and A with the previously described results, which are that a universal switcher in Akard, the universal switcher US' for example, is seized. It will be assumed that the universal switcher
30 US' is seized at this time, as before, by way of the universal switcher US, secondary switch D', repeater R', and the selectors E and F'. It will be assumed further that the secondary switch D² associated with the universal switcher US' seizes the repeater R², with the consequent result that the selector G² in Ghent, Fig. 6, is prepared for operation in the usual manner. It will be assumed still further that the secondary switch D⁶ associated with the universal switcher US', seizes the repeater R⁴, which results in the incoming selector associated therewith in Topaz being prepared for
40 operation in the usual manner.

45 When the calling subscriber operates his calling device in accordance with the next and third letter H in the name of the desired office, four interruptions are produced in the circuit of line relay 244 of the universal switcher US' by the operation of the line relay 186 of the repeater R', which line relay is controlled by the calling device at the calling substation, and upon each of the four momentary deenergizations, line relay 244 opens the circuit of impulse relays 266 and 269. Relay 266 in turn, upon de-energizing, interrupts the circuit of line relay 216 of the repeater R², which in turn interrupts the circuit of the line relay (not shown) of the selector G². As a result, the wipers of the selector G² are raised to the fourth level, and are then rotated in search of an idle trunk. Upon referring to Fig. 9, it will be noted that the fourth level of the selector G² is dead, and consequently its

trunk selecting operation is of no utility at this time.

Impulse relay 269 of the universal switcher US', upon deenergizing in response to each of the interruptions produced in its circuit by line relay 244, interrupts the circuit of the line relay of the repeater R⁴, which line relay in turn interrupts the circuit of the line relay of the associated selector G', Fig. 9, in Topaz. As a result, the selector G' raises its wipers to the fourth level, and rotates them in search of an idle trunk. Assuming that the trunk extending to the secondary switch D¹³ is the first one found to be idle, the said switch D¹³, upon being seized, selects an idle repeater, which repeater, it will be assumed, is the repeater R⁸. That being the case, the incoming selector H⁴, in Mahope, is prepared for operation in the usual manner. 85

In the universal switcher US', as a further result of each deenergization of line relay 244, it closes the usual circuit for stepping magnet 247, and as a result wiper 249 is advanced into engagement with the fourth bank contact 261. Series relay 246, upon deenergizing at the end of the series of impulses delivered to the stepping magnet, closes the usual circuit for release magnet 248. Wiper 249, being upon contact 261, extends the circuit to seizing relay 268. Seizing relay 268, upon energizing, closes the usual locking circuit for itself at armature 280. Release magnet 248, upon energizing, disconnects wiper 249 at armature 262 and restores it to normal position in the usual manner, its circuit being opened at off normal contacts 250 when wiper 249 reaches normal position. As a further result of the energization of seizing relay 268, it connects release trunk conductor 241 with release trunk conductor 292 of the switch D⁸ at armature 281; closes a circuit for cut off relay 243 at armature 279; and at armatures 278 and 282 connects line conductors 240 and 242 with line conductors 291 and 293 of the switch D⁶. Cut off relay 243, upon energizing, disconnects ground from armature 255 of line relay 244 at armature 253, and at armatures 251 and 252 disconnects line relay 244 from trunk conductors 240 and 242. Line relay 244, upon deenergizing, opens the circuit of impulse relays 266 and 269 at armature 254. Impulse relay 266, upon deenergizing, opens the bridge across conductors 285 and 287 at armature 283, whereupon the connection to Ghent is released in the usual manner. Impulse relay 269, upon deenergizing, opens the local bridge across conductors 291 and 293 at armatures 284, thereby leaving the control of the line relay of the repeater R⁴ with line relay 186 of the repeater R'. Release relay 245, upon deenergizing, disconnects ground from release trunk conductor 241 at armature 254.

ture 256, leaving the said conductor grounded by way of the holding circuit which extends back from the release relay of the repeater R⁴.

- 5 The calling subscriber may now proceed to dial the four digits in the desired number with the result that the selector H² in Mahope to which a connection has been extended, a local hundreds selector, and a connector, operate to extend the connection to the called line in the usual manner. After the connection has been completed, and the conversation terminated, the connection is released in the usual manner when the receiver is replaced at the calling substation.

It will be assumed now that the calling subscriber at substation A has dialed the first two letters M and A of an office name, and that the connection has taken the previously pointed out route to the universal switcher US', and thence to Ghent and to Topaz. With the assumption as noted, and assuming further that the calling subscriber is calling a subscriber in neither Main nor Mahope, but is calling a subscriber in Macey, two interruptions are produced in the circuit of line relay 244 of the universal switcher US', when the next and third letter C of the office name is dialed. That being the case, impulse relays 266 and 269 repeat two interruptions on toward the selectors to which the connection has been extended in Topaz and in Ghent. As a result the selectors raise their wipers to the second level and rotate them in search of idle trunks. This, however, does not perform any useful function for the reason that the second level of the selector G², Fig. 9, in Ghent is dead, and likewise the second level of the selector G' in Topaz.

In the universal switcher US', two impulses of current are delivered to the stepping magnet 247, and consequently wiper 249 is stepped into engagement with the second associated bank contact. When series relay 246 deenergizes at the end of the series of impulses, the usual circuit is closed for release magnet 248 by way of off normal contacts 250 and, since wiper 249 is standing on the second bank contact 260, a circuit is closed in multiple with release magnet 248 for seizing relay 267, which seizing relay 267, upon energizing, closes the usual locking circuit for itself at armature 276. Release magnet 248, of course, energizes, disconnects wiper 249, and restores it to normal position in the usual manner. As a further result of the energization of seizing relay 267, it connects release trunk conductor 241 with release trunk conductor 289 of the secondary switch D' at armature 235; connects conductors 240 and 242 with conductors 288 and 290 at armatures 274 and 277; and at armature 275 closes the usual circuit for cut off relay 243, which relay 243, upon

energizing, disconnects line relay 244, and opens the circuit of release relay 245. Line relay 244, upon deenergizing, opens the circuit of impulse relays 266 and 269 at armature 254, whereupon the connection to Ghent and the connection to Topaz is released in the usual manner.

In response to conductors 240 and 242 being connected with conductors 288 and 290 of the secondary switch D', the line relay thereof energizes, thereby starting the trunk hunting movement and placing ground upon release trunk conductor 289 in the usual manner before the slow acting release relay 245 of the universal switcher US' has had time to deenergize. The secondary switch D' operates in the usual manner to select an idle trunk, which trunk it will be assumed is the one extending to the repeater R⁵. That being the case, the line and release relays thereof energize in the usual manner, with the result that the incoming selector H², Fig. 9, in Macey, is prepared for operation in the usual manner.

The calling subscriber now proceeds to dial the four digits in the desired number in the usual manner, whereupon the selector H², Fig. 9, a local hundreds selector, and a connector, in Macey, operate to extend the connection to the called line. After the connection has been completed and the conversation has terminated, the release is effected in the usual manner, upon the receiver being replaced at the calling substation.

It will be noted, that in the previously described connection, the connection was extended from the universal switcher US' direct to the fourth selector H² without being extended through a third selector, thus eliminating one of the switches ordinarily used in a connection.

It will be assumed now that the subscriber at substation A desires to call a subscriber whose line terminates in the Southern office, which office is reached by way of Ghent, Figs. 8 and 9. It will be noted that the first two letters of the name Southern, which are numerically 7 and 0, conflict with the first two letters T and O in Topaz, and consequently, upon S and O being dialed, it will be necessary to take a trunk not only to Ghent, but also to Topaz.

When the receiver is removed at the calling substation, the hereinbefore described operations take place, with the result that a universal switcher, the universal switcher US for example, is seized, and, assuming that the associated rotary switch D', seizes the repeater R', Fig. 2, the selector E, Fig. 3 is prepared for operation in the usual manner.

In response to the calling of the first letter S in the office name, seven interruptions are produced in the circuit of line relay 210, of

the selector E, in the usual manner, whereupon the said selector E raises its wipers 230-232, inclusive, to the seventh level, and picks out an idle trunk. Assuming that the 5 trunk extending to the selector F⁴ is the first one found to be idle, and consequently the one selected, the line and release relays of the said selector F⁴ energize, thereby preparing the switch for operation, and establishing 10 the usual holding circuit for the selector E, in the usual manner.

In response to the calling of the second letter O in the office name, the selector F⁴ raises its wipers to the tenth level and rotates them in search of an idle trunk. Assuming that the trunk extending to the universal switcher US², Fig. 4, and comprising conductors 401-403, inclusive, to be the first one found to be idle and consequently the 20 one selected, line relay 405, upon energizing, in response to the line conductors being switched through by the switching relay (not shown) of the selector F⁴, closes a circuit for release relay 406 at armature 412. 25 Release relay 406, upon energizing, prepares a circuit for stepping magnet 430 at armature 413, and at armature 419 places ground upon release trunk conductor 402, thereby establishing the usual holding circuit for the 30 switching relays of the selectors E and F⁴. As a further result of the energization of line relay 405, it closes at armature 411 a circuit for impulse relays 416 and 418, in multiple, and these relays, upon energizing, 35 close the usual local bridges across the associated trunk conductors at armatures 445 and 451. When this occurs, the secondary switches D⁹ and D¹⁰ operate to select idle trunks in the usual manner, which trunks it 40 will be assumed are the ones extending to the repeaters R² and R⁴. That being the case, the said repeaters R² and R⁴ operate in the usual manner, upon being seized, to establish the usual holding circuits, and to 45 prepare the distant associated selectors for operation in the usual manner. The repeater R², for example, prepares the selector G², Fig. 6, for operation, by closing a bridge across conductors 325 and 326 at armature 318 of line relay 315.

The calling subscriber now operates his calling device in accordance with the third letter U in the office name, thereby causing eight interruptions to be produced in the circuit of line relay 405, of the universal switcher US², Fig. 4. In response to these interruptions produced in its circuit, line relay 405 interrupts the circuit of impulse relays 416 and 418 a like number of times at armature 411. These interruptions are repeated by impulse relays 416 and 418, by way of the repeaters R² and R⁴, to the respective associated selectors in the offices Ghent and Topaz. When this occurs, the 50 selector G², Figs. 6 and 9, and the selector

F', Fig. 9, operate in the usual manner, thereby raising their wipers to the eighth level and rotating them in search of idle trunks. It will be noted that there are no trunks accessible to the selector G' on the 70 eighth level, and consequently its trunk selecting operation is of no avail. The selector G², however, in Ghent, upon being raised to the eighth level, selects a trunk to Southern by way of the usual outgoing secondary switch and repeater (not shown). 75

In the universal switcher US², Fig. 4, line relay 405 upon responding to the eight interruptions produced in its circuit upon the calling of the third letter U in the office name, not only interrupts the circuit of impulse relays 416 and 418, as described, but also operates stepping magnet 430 over the following circuit: From ground by way of the resting contact of armature 410 and said armature, armature 412 and its resting contact, line relay 407, and stepping magnet 430 to battery, whereupon wiper 434 is advanced step by step until it comes to rest upon the eighth associated bank contact 436. 90 Relay 407 is energized in series with stepping magnet 430 and, being slow acting, retains its armature attracted throughout the series of interruptions. Upon deenergizing at the end of the series of interruptions, relay 95 407 closes a circuit for release magnet 431 at armature 414, by way of off normal contacts 432. Release magnet 431, however, owing to its comparatively heavy armature and to the stiff spring adjustments is slightly hesitant about energizing and seizing relay 415 is energized in multiple with release magnet 431, by way of armature 433 and its resting contact, wiper 434, and bank contact 436. 100 Upon energizing, relay 415 closes a locking circuit for itself at armature 442 before release magnet 431 has had time to energize. Release magnet 431, upon energizing, disconnects wiper 434 at armature 433, and restores it to normal, its circuit being opened 110 at off normal contacts 432 when it reaches normal position. As a further result of the energization of seizing relay 415, it connects release trunk conductor 402 with the release trunk conductor of the switch D¹⁰ at 115 armature 443; connects line conductors 401 and 403 with the line conductors of the switch D¹⁰ at armatures 440 and 444; and at armature 441 closes a circuit for cut off relay 404. Relay 404, upon energizing, disconnects ground from armature 412 of line 120 relay 405 at armature 410, and at armatures 408 and 409 disconnects conductors 401 and 403 from the windings of line relay 405. Line relay 405, upon deenergizing, opens the circuit of impulse relays 416 and 418, at armature 411. Relay 416, upon deenergizing, removes the local bridge from across the line conductors of the trunk extending to the switch D¹⁰, leaving the line relay of 125 130

the repeater R^2 , Fig. 5, to which the connection has been extended, under the direct control of the line relay of the repeater R' , Fig. 2. Relay 418, upon deenergizing, removes the bridge from across the associated line conductors, whereupon the connection to Topaz is released in the usual manner.

The calling subscriber now operates his calling device in accordance with the digits in the desired number. Whereupon the local switches in the Southern office (not shown), comprising a fourth and a fifth selector, and a connector, operate in the usual manner to extend the connection to the desired line. After the called subscriber has answered, and the conversation has been completed, the switches are released in the usual manner, upon the receiver being replaced at the calling substation.

Referring now again to the universal switcher US^2 , Fig. 4, it may be stated that, after a connection is extended to it, if the calling subscriber is calling a subscriber in Topaz instead of Southern, the wiper 434 is moved into engagement with the sixth bank contact 435, upon the calling of the third letter P in the office name. In this case, seizing relay 417 is energized instead of seizing relay 415, and the connection is extended by way of the switch D^9 , and the connection to Ghent is released.

It will be assumed now that the subscriber at substation A desires to converse with some subscriber whose line terminates in the office Akard, or a branch office thereof. Assuming that the universal switcher US is seized by the line switch C when the receiver is removed at substation A and that the secondary switch D' seizes the repeater R' , the selector E in Akard is prepared for operation in the usual manner.

In response to the calling of the first letter A, one interruption is produced in the circuit of line relay 26, of the universal switcher US' , which interruption is repeated by impulse relay 36 to the line relay 186 of the repeater R^2 and thence to the selector E, Fig. 3, which selector responds by raising its wipers to the first level and selecting an idle trunk in the usual manner, the trunk extending to the selector F, Fig. 9, for example. In the universal switcher US , one impulse of current is delivered to stepping magnet 90 at armature 49 of line relay 26, and its resting contact. When this occurs, wiper 99 is advanced into engagement with the first bank contact 94, and series relay 28, upon deenergizing after the impulse is delivered, closes at armature 53 a circuit for release magnet 91, by way of off normal contacts 93. Release magnet 91, however, as hereinbefore stated, is stiffly adjusted and has a heavy armature and consequently does not energize as quickly as it otherwise would. As a result, before armature 92 is operated,

relays 29 and 30 energize in series over the following circuit: From ground by way of the resting contact of armature 53 and said armature, off normal contacts 93, armature 92 and its resting contact, lower winding of relay 29, wiper 99, bank contact 94, resting contact of armature 57 and said armature, and the lower winding of relay 30 to battery. Relay 29, upon energizing, closes a locking bridge for itself in multiple with release magnet 91, at the lightly adjusted armature 54, and at armature 55 opens a point in the circuit of seizing relay 35. Relay 30, upon energizing, closes a locking circuit for itself by way of its upper winding at the lightly adjusted armature 56, immediately, but does not operate the more stiffly adjusted armatures 57 and 58 until a fraction of a second later, thereby allowing ample time for relay 29 to operate as above explained. Upon energizing fully, relay 30 prepares a circuit for relay 31 at armature 58, and at armature 57 opens the circuit of its own lower winding and the lower winding of relay 29. Release magnet 91, upon energizing a fraction of a second after the circuit is closed, disconnects the lower winding of relay 29 and consequently wiper 99, from its own winding at armature 92, at the same time closing a point in the circuit of relay 35. Relay 35 does not energize at this time, however, because its circuit is open at armature 55 of relay 29. As a further result of the energization of the release magnet 91, wiper 99 is restored to normal position, whereupon the circuit of release magnet 91 and the circuit of the upper winding of relay 29 is opened at off normal contacts 93. When this occurs, relay 29 and magnet 91 deenergize.

The calling subscriber now operates his calling device in accordance with the second letter K in the desired number, thereby producing five interruptions in the circuit of line relay 26 of the universal switcher US . In response to these interruptions being repeated in the usual manner over the connection extending to Akard, the selector F, Fig. 9, to which the connection has been extended, raises its wipers to the fifth level and rotates them in search of an idle trunk. Assuming the trunk extending to the selector G to be the first one found to be idle, and consequently the one selected, the said selector G is prepared for operation in the usual manner.

In the originating branch exchange, line relay 26 of the universal switcher US , upon deenergizing in response to each of the five interruptions produced in its circuit, closes the usual circuit for stepping magnet 90, and as a result, wiper 99 is brought into engagement with the fifth associated bank contact 95. When series relay 28 falls back at the end of the stepping movement, it closes the usual circuit for release magnet 91, by way of off normal contacts 93. A branch of this

circuit extends, at this time, by way of armature 92 and its resting contact, lower winding of relay 29, wiper 99, bank contact 95, armature 58 and its working contact, resting contact of armature 60 and said armature, and the lower winding of relay 31 to battery. In response to this circuit being closed, relay 29, upon energizing, opens a point in the circuit of relay 35 at armature 55 and closes the usual locking circuit for itself at armature 54. Relay 31, which, together with relays 32 and 33, is adjusted in the same manner as relay 30, upon energizing, closes a locking circuit for itself at armature 59; opens its initial circuit and the circuit of the lower winding of relay 29 at armature 60; and at armature 61 connects the first bank contact 94 with the lower winding of relay 32. Release magnet 91, upon energizing, restores wiper 99 to normal position in the usual manner, whereupon its circuit and the locking circuit of relay 29 are opened at armature 92.

In response to the calling of the third letter A in the office name, one interruption is produced in the circuit of the line relay of the selector G, Fig. 9, in the usual manner. When this occurs, the said selector G raises its wipers to the first level, and picks out an idle trunk, the trunk extending to the selector H for example.

In the universal switcher US, stepping magnet 90, upon being operated, steps wiper 99 into engagement with the first bank contact 94, and series relay 28, upon falling back subsequently, closes the usual circuit for release magnet 91 and also a circuit which extends, as before traced, to wiper 99 and thence by way of bank contact 94, armature 61 and its working contact, resting contact of armature 66 and said armature, and the lower winding of relay 32 to battery. In response to the closing of this circuit, relay 29 energizes with the hereinbefore described results, and relay 32 upon energizing, closes a locking circuit for itself at armature 62; opens its initial circuit at armature 63; prepares a circuit for the lower winding of relay 33 at armature 64; and at armature 65 prepares a circuit for the upper winding of relay 34.

Assuming now that the desired subscriber's line terminates not in the main office Akard, but in the 6000 branch thereof, which is the branch in which the call originated, six interruptions are produced in the circuit of line relay 26 of the universal switcher US when the first digit 6 in the desired number is called. These interruptions are repeated in the usual manner to the selector H, Fig. 9, whereupon it raises its wipers to the sixth level and rotates them and picks out an idle trunk, the one extending to the secondary switch D^{15} for example. The switch D^{15} upon operating, selects an idle

trunk to the 6000 branch of Akard, the trunk extending by way of the repeater R^3 to the incoming selector I^2 for example.

In the originating branch exchange, line relay 26 of the universal switcher US, sends six impulses of current to stepping magnet 90, and as a result wiper 99 is advanced into engagement with the sixth bank contact 96. Series relay 28 upon deenergizing at the end of the series of impulses, closes the usual circuit for release magnet 91 at armature 52, by way of off normal contacts 53. A branch of this circuit extends over the previously traced path to wiper 99, and thence by way of the sixth bank contact 96, armature 65 and its working contact, armature 85 and its resting contact, and the upper winding of relay 34 to battery. Relays 29 and 34 energize in series over this circuit. Relay 29, upon energizing, closes the usual locking circuit for itself in multiple with release magnet 91 at armature 54, and opens a point in the circuit of relay 35 at armature 55. Relay 34, upon energizing, closes a locking circuit for itself at its lightly adjusted armature 71, immediately; connects release trunk conductor 20 with release trunk conductor 106 of the secondary switch D^2 at armature 72; connects line conductors 19 and 21 with conductors 105 and 107 of the secondary switch D^2 at armatures 69 and 73; and at armature 70 closes a circuit for cut off relay 25. Cut off relay 25, upon energizing, disconnects ground from armature 49 of line relay 26 at armature 46, thereby opening the circuit of release relay 27, and at armatures 45 and 47 disconnects conductors 19 and 21 from the windings of line relay 26. Line relay 26, upon deenergizing, opens the circuit of impulse relay 36 at armature 48. Impulse relay 36, upon deenergizing, removes the local bridge from across conductors 108 and 110, at armature 79, whereupon the connection to Akard, and from Akard to the originating branch office, is released in the usual manner.

In response to the line conductors 19 and 21 being connected with conductors 105 and 107 of the secondary switch D^2 , line relay 121 energizes over the calling subscriber's loop, and upon doing so, places ground upon release trunk conductor 106 at armature 129, thereby establishing a holding circuit for relays 25 and 34 in the universal switcher US, and for switching relay 5 of the line switch C. This circuit, of course, is established before the slow acting release relay 27, of the universal switcher US, deenergizes.

In the secondary switch D^2 , as a further result of the energization of line relay 121, it completes a circuit for switching relay 120 and stepping magnet 122 in series at armature 128, and at armature 127 connects test wiper 131 to the circuit between switching

relay 120 and stepping magnet 122. The switch D² now operates in the usual manner to select an idle trunk and, upon one being found, which trunk it will be assumed is the one extending to the selector I, switching relay 120, being no longer short circuited, energizes in series with stepping magnet 122; opens test circuit and prepares the holding circuit at armature 125; places a shunt around armature 128 and its working contact at armature 124; and at armatures 123 and 126 disconnects conductors 105 and 107 from the windings of line relay 121 and ground respectively, and extends them by way of wipers 130 and 132, the bank contacts with which said wipers 130 and 132 are in engagement, conductors 133 and 135, and armatures 156 and 159, to the upper and lower windings of line relay 140 of the selector I. Line relay 140, upon energizing over the calling subscriber's loop, closes a circuit for release relay 141 at armature 150. Release relay 141, upon energizing, opens a point in the circuit of release magnet 145 and prepares a circuit for vertical magnet 147 at armature 152, and at armature 151 places ground upon release trunk conductor 134, thereby establishing the usual holding circuit before the slow acting relay 121 of the switch D² has had time to deenergize.

In response to the calling of the three remaining digits in the desired number, the connection is extended by way of the seized selector I, and a local connector, to the desired line, and after the called subscriber has responded, and the conversation has terminated, the connection is released in the usual manner, when the receiver is replaced at the calling substation.

It will be assumed now that the subscriber at substation A is making a call and that he has dialed the letters A, K and A of the Akard office, with the result that the relays 30-32, inclusive, of the universal switcher US, Fig. 1, have been operated in the previously described manner and that the connection has been extended over the previously pointed out path to Akard, and thence by way of the selectors F and G to the selector E, Fig. 9. With the assumption as noted above, and assuming further that the subscriber at substation A is calling a subscriber in the 9000 group of Akard, which is the group in which the 100 lines of the 9700 branch of Akard, Fig. 9, belong, the nine interruptions produced in the circuit of line relay 26 of the universal switcher US in response to the dialing of the next digit in the desired number, are repeated in the usual manner to the selector H, Fig. 9. The selector H now raises its wipers to the ninth level and picks out an idle trunk, the trunk extending to the selector I for example.

In the universal switcher US, Fig. 1, nine

impulses are delivered to the stepping magnet 90 at this time, and as a result, wiper 99 is advanced into engagement with the ninth associated bank contact 98. Series relay 28, upon de-energizing at the end of the series of im-⁷⁰ pulses, closes the usual circuit for release magnet 91. A branch of this circuit extends by way of armature 92 and its resting contact, lower winding of relay 29, wiper 99, bank contact 98, armature 64 and its work-⁷⁵ ing contact, resting contact of armature 67 and said armature, and the lower winding of relay 35 to battery. Relays 33 and 29 energize in series over this circuit, and relay 29, upon energizing, closes a locking circuit for itself in multiple with release magnet 91 at armature 54, and at armature 55 opens a point in the circuit of relay 35. Relay 33, upon energizing, closes a locking circuit for itself at armature 66; opens its initial cir-⁸⁵ cuit at armature 67; opens a point in the circuit of relay 34 at armature 85; and at armature 69 prepares a circuit for the upper winding of relay 37.

Assuming now that the subscriber at sub-⁹⁰ station A is calling a subscriber in the 9700 branch of Akard, he now operates his calling device in accordance with the next digit 7 in the desired number, whereupon the selector I in Akard, Fig. 9, raises its wipers to the seventh level and selects an idle trunk, the trunk extending to the secondary switch D⁷ for example. The switch D⁷ now operates to select an idle trunk to the 9700 branch of Akard, the trunk extending by way of the repeater R⁷ and terminating in the connec-¹⁰⁰ tor J⁷ for example.

In the universal switcher US, seven im-¹⁰⁵ pulses of current are delivered to stepping magnet 90, and as a result, wiper 99 is ad-¹¹⁰vanced into engagement with the seventh associated bank contact 97. When series relay 28 falls back at the end of the series of interruptions, it closes the usual circuit for stepping magnet 91, whereupon ground is ex-¹¹⁵tended by way of the lower winding of the relay 29 to wiper 99, and thence by way of the seventh bank contact 97, armature 68 and its working contact, and the upper winding of seizing relay 37 to battery. Re-¹²⁰lays 29 and 37 energize in series over this circuit. Relay 29, upon energizing, per-¹²⁵forms the hereinbefore described operations, and relay 37, upon energizing, closes a lock-¹³⁰ing circuit for itself at its lightly adjusted armature 82; connects release trunk conductor 120 with release trunk conductor 112 of the secondary switch D², at armature 83; connects conductors 19 and 21 with conductors 111 and 113 of the secondary switch D at armatures 80 and 84; and at armature 81 closes a circuit for cut off relay 25 of the universal switcher US. By the operation of cut off relay 25, the circuits of line relay 26 and release relay 27 are opened. Line relay 130

26, upon deenergizing opens the circuit of impulse relay 36 at armature 48, whereupon the connection to Akard and from Akard back to the 9700 branch is released in the 5 usual manner.

In response to the line conductors of the universal switcher US being extended to the conductors 111 and 113 of the secondary switch D, the line relay of the said secondary switch D, places ground upon the associated release trunk conductor 112, thereby establishing the usual holding circuit for the relays of the universal switcher US and for the switching relay of the line switch C 10 before the slow acting relay 27 of the universal switcher US has had time to deenergize. As a further result of the energization of the line relay of the secondary switch D, an idle trunk to the 9700 branch of Akard 15 is seized, which trunk it will be assumed, is the one extending by way of the repeater R. That being the case, the repeater R, upon being seized, closes a bridge across the associated outgoing trunk conductors, whereupon the connector J², Fig. 9, in the 9700 20 branch of Akard, is prepared for operation in the usual manner.

In response to the calling of the two remaining digits in the desired number, the 30 connection is completed in the usual manner, and after the conversation is completed the connection is released in the usual manner when the receiver is replaced at the calling substation.

35 Referring now again to the universal switcher US, Fig. 1, it will be noted that the seizing relay 35 which is associated with the secondary switch D', which switch has access to trunks to Akard is kept from energizing when the release magnet 91 of the universal switcher US energizes, only by the energization of relay 29, which relay is energized in series with any relay with which wiper 99 happens at that time to be connected. It will be seen therefore, that if wiper 99 is standing upon a contact with which no relay is connected, relay 29 will fail to energize when the circuit of release magnet 91 is closed and relay 33 will be operated upon the energization of release magnet 91, which will result in the route to Akard being definitely seized in the hereinbefore described manner, after which the dialing of the remaining part of the number 40 does not cause any operation to take place in the universal switcher US. Summing it up then, the universal switcher US operates only so long as the characters of the number being called are such that the calling of the remaining part of the number 45 may route the call either to the local branch or to the 9700 branch of Akard.

At this point it may be mentioned that, while all the foregoing detailed descriptions 50 have been given from the standpoint of a

subscriber at the substation A' in the 6000 branch of Akard, it is not considered necessary to give a detailed description of any connections set up by the subscriber at substation A' in Akard. It will suffice to say 70 that calls from the substation A' are completed as pointed out in the preliminary part of the specification and that the operation of any particular switch when employed in setting up a connection is the same regardless of from which substation a call is being made. 75

The various features of the invention, having been described and ascertained thus, will now be pointed out in the appended claims. 80

What is claimed is:

1. In a multi-office automatic telephone system, means responsive to the calling of a part of a called number for extending a connection from an office to each of a plurality 85 of other offices over separate paths, and means responsive to the calling of a second part of the number for operating switches in all of said other offices and for subsequently releasing the connections to all of 90 said other offices except the one by way of which the called line is reached.

2. In an automatic telephone system, an office, a plurality of other offices, means responsive to impulses representing a part of 95 a called number for extending a connection from the first named office to each of said other offices over separate paths, and means responsive to impulses representing a second part of said called number for operating 100 switches in all of said other offices and for subsequently releasing the connections to all of said other offices. 100

3. In a telephone system, a calling line, a plurality of called lines and a number assigned to each, a switching device, means responsive to the calling of the first part of one of said numbers for extending a connection from said calling line to said switching device, means responsive to the seizure 105 of said device for extending a connection therefrom to each of a plurality of distant switching centers over separate paths, and means responsive to the calling of a second part of the number for simultaneously operating switches in each of said switching centers and for subsequently releasing the connection to any desired switching center, the connection released depending upon the 110 number called. 115

4. In a telephone system, a calling line, a plurality of called lines and a number assigned to each, a switching device, a plurality of switching mechanisms, means for extending a connection from the calling line 125 to said device, means responsive to the seizure of said device for extending a connection therefrom over a separate path to each of said switching mechanisms, and means responsive to the calling of a part of 130

- the number assigned to a called line for simultaneously operating said switching mechanisms and for subsequently releasing certain ones of said connections, the ones released depending upon the number called.
5. In a telephone system, a calling line, a called line and a number assigned thereto, a switching device, a plurality of switching mechanisms, another switching mechanism, means for seizing said switching device by extending a connection from said calling line thereto, means responsive to said seizure for extending a connection from said device over separate paths to each of said plurality of switching mechanisms, means responsive to the calling of a part of a number of said line for operating each of said plurality of mechanisms, means responsive to said calling for extending a connection from said device to said other mechanism, and means responsive to said calling for releasing all of said connections to said plurality of mechanisms.
6. In a telephone system, a calling line, a called line and a number assigned thereto, a switching device having a line relay, means responsive to the calling of the first part of the number of said called line for seizing said device by extending a connection from said calling line thereto, means responsive to said seizure for energizing said line relay, a plurality of paths outgoing from said device and leading to switching mechanisms, an impulse relay associated with each of said paths, means responsive to the energization of said line relay for extending a connection from said device over all of said paths by energizing said impulse relays, and means responsive to the calling of a second part of the number for simultaneously operating said switching mechanisms and for subsequently releasing the connection extending over any desired path, the connection released depending upon the number called.
7. In a telephone system, a switching device, said device having a line relay and a plurality of repeating relays, a separate outgoing trunk associated with each of said repeating relays, means for extending a connection to said device and for energizing said line relay, circuit connections controlled by said line relay for thereupon energizing said repeating relays, means responsive to said energization of each of said repeating relays for extending a connection over the associated trunk, means for producing momentary interruptions in the circuit of said line relay, and means controlled by said line relay in response to said interruptions for causing each of said repeating relays to send a like number of switch control impulses over the associated trunk.
8. In a telephone system, a switching device, said device having a line relay and a plurality of repeating relays, a separate outgoing trunk associated with each of said repeating relays, said trunks being normally disconnected from said device, means for extending a connection to said device and for energizing said line relay, circuit connections controlled by said line relay for simultaneously energizing each of said repeating relays, means responsive to the energization of each of said repeating relays for extending a connection from said device over the associated trunk, means for producing momentary interruptions in the circuit of said line relay, and means controlled by said line relay for causing each of said repeating relays to send a switch control impulse over the associated trunk for each of said interruptions.
9. In a telephone system, a switching device, said device having a line relay, a cut off relay, and a plurality of repeating relays, a trunk associated with each of said repeating relays, a seizing relay associated with each of said trunks, another seizing relay, a recording mechanism associated with said device, means for extending a connection to said device and for energizing said line relay, means responsive to the energization of said line relay for extending a connection over each of said trunks by energizing said repeating relays, means responsive to the calling of a part of a desired number for deenergizing said line relay a plurality of times, means responsive to each deenergization of said line relay for operating said recording mechanism and for simultaneously deenergizing said repeating relays, means responsive to each deenergization of each of said repeating relays for sending a switch control impulse over the associated trunk means controlled by said recording mechanism for energizing said other seizing relay, the seizing relay energized in any case depending upon the number called, means responsive to the energization of said other seizing relay for energizing said cut off relay, and means responsive to the energization of said cut off relay for releasing the connection established over each of said trunks.
10. In a telephone system, a switching device, said device having a line relay, a cut off relay, and a plurality of repeating relays, a trunk associated with each of said repeating relays, a seizing relay associated with each of said trunks, a recording mechanism associated with said device, means for extending a connection to said device and for energizing said line relay, means responsive to the energization of said line relay for extending a connection over each of said trunks by energizing said repeating relays, means responsive to the calling of a part of a desired number for deenergizing said

line relay a corresponding number of times, means responsive to each deenergization of said line relay for operating said recording mechanism and for simultaneously deenergizing said repeating relays, means responsive to each deenergization of each of said repeating relays for sending a switch control impulse over the associated trunk, means controlled by said recording mechanism in response to said operation thereof for energizing one of said seizing relays, the relay energized depending upon the number called, means responsive to the energization of the last named seizing relay for connecting said device with the trunk associated with said last named seizing relay, a second means responsive to the energization of said last named seizing relay for energizing said cut off relay, and means responsive to the energization of said cut off relay for releasing the connection established over each of said trunks with the exception of the one established over the trunk with which said last named seizing relay is associated. 90

11. In a telephone system, a switching device, said device having a line relay, a cut off relay, and a plurality of repeating relays, a trunk associated with each of said repeating relays, a seizing relay associated with each of said trunks, another seizing relay, a recording mechanism associated with said device, means for extending a connection to said device and for energizing said line relay, means responsive to the energization of said line relay for extending a connection over each of said trunks by energizing said repeating relays, means responsive to the calling of a desired number for deenergizing said line relay a plurality of times, means responsive to each deenergization of said line relay for operating said recording mechanism and for simultaneously deenergizing said repeating relays, means responsive to each deenergization of each of said repeating relays for sending a switch control impulse over the associated trunk, means controlled by said recording mechanism for energizing said other seizing relay, the seizing relay energized in any case depending upon the number called, another trunk associated with said last named seizing relay, means responsive to the energization of said other seizing relay for connecting said device with said other trunk, means responsive to the energization of the last named seizing relay for energizing said cut off relay, and means responsive to the energization of said cut off relay for releasing the connection established over each of said plurality of trunks. 125

12. In a telephone system, a switching device, said device having a line relay and a repeating relay, a trunk outgoing from said device associated with said repeating relay,

a seizing relay associated with said trunk, a second trunk and a seizing relay associated therewith, a recording mechanism associated with said device, means for extending a connection to said device and for energizing said line relay, means responsive to said energization of said line relay for extending a connection over said trunk by energizing said repeating relay, means responsive to the calling of a part of a desired number for deenergizing said line relay a corresponding number of times, means responsive to each deenergization of said line relay for operating said recording mechanism and for simultaneously deenergizing said repeating relay, means responsive to each deenergization of said repeating relay for sending a switch control impulse over the associated trunk, means controlled by said recording mechanism for energizing one of said seizing relays, the relay energized depending upon the number called, and means responsive to the energization of either of said seizing relays for connecting said device with the associated trunk and for rendering said recording mechanism unresponsive to the calling of the remaining part of the number by energizing said cut off relay. 90

13. In a telephone system, a switching device, said device having a line relay and a repeating relay, a trunk outgoing from said device associated with said repeating relay, a seizing relay associated with said trunk, a second trunk and a seizing relay associated therewith, a recording mechanism associated with said device, means for extending a connection to said device and for energizing said line relay, means responsive to said energization of said line relay for extending a connection over said trunk by energizing said repeating relay, means responsive to the calling of a desired number for deenergizing said line relay a corresponding number of times, means responsive to each deenergization of said line relay for operating said recording mechanism and for simultaneously deenergizing said repeating relay, means responsive to each deenergization of said repeating relay for sending a switch control impulse over the associated trunk, means controlled by said recording mechanism for energizing one of said seizing relays, the relay energized depending upon the number called, means responsive to the energization of said second seizing relay for connecting said device with said second trunk and for energizing said cut off relay, and means controlled by the energization of said cut off relay for rendering said recording mechanism inoperative and for releasing the connection established over said first trunk. 120

14. In a telephone system, a calling line, a plurality of called lines having telephone numbers in which the initial characters are 130

- the same, automatic switching mechanism controlled by the calling subscriber for setting up connections toward all of said called lines simultaneously, and means for releasing all of said connections except one as soon as a character is called which determines which of the called lines is the one wanted.
15. In a telephone system, automatic subscriber controlled switching mechanism for simultaneously setting up a plurality of partially established connections in accordance with a plurality of characters in a called telephone number, and means for automatically releasing all of said connections except the one needed to complete the connection to the called line.
16. In a telephone system, automatic subscriber controlled switching mechanism for simultaneously setting up a plurality of partially established connections in accordance with a plurality of characters in a called telephone number, subscriber controlled registering mechanism set simultaneously with the establishment of said connections, and means controlled by said registering mechanism for releasing all of said connections except the one needed to connect with the called line.
- 20 17. In a telephone system, a plurality of trains of automatic switches, a trunk line common to said switch trains, means for extending a calling line to said trunk line, means controlled by the calling subscriber for actuating the switches in one of said trains to extend a connection toward the desired called line and to simultaneously actuate the switches in the other trains, and means in said trunk line for subsequently releasing all of said switch trains except the one needed to complete the desired connection.
- 25 18. In a telephone system, a plurality of trains of automatic switches, a trunk line common to said switch trains, means for extending a calling line to said trunk line, means controlled by the calling subscriber for actuating the switches in one of said trains to extend a connection toward the desired called line and to simultaneously actuate the switches in the other trains, registering mechanism associated with said trunk line operated simultaneously with the switches in said trains, and means controlled 30 in accordance with the setting of said mechanism for releasing all of said switch trains except the one needed to complete the required connection.
- 35 19. In a telephone system, a trunk line having a plurality of normally disconnected branches, means for extending a calling line to said trunk line, a repeating relay in said trunk line controlled by the calling subscriber in accordance with a plurality of digits in a called number to repeat impulses over said branches, a train of automatic switches associated with each branch and responsive to said impulses, and means for automatically releasing all of said switch trains except the one needed to connect with the called line.
- 40 20. In a telephone system, a trunk line having a plurality of normally disconnected branches, means for extending a calling line to said trunk line, a repeating relay in said trunk line controlled by the calling subscriber in accordance with a plurality of digits in a called number to repeat impulses over said branches, a train of automatic switches associated with each branch and responsive to said impulses, registering mechanism also controlled by said repeating relay, and means controlled by said registering mechanism for releasing all of said switch trains except the one needed to connect with the called line.
- 45 21. In a telephone system, a trunk with three branches, three branch connecting relays, registering means individual to said trunk for registering digits in a telephone number, and means responsive to the registration of a particular series of digits for energizing a particular one of said relays, the relay energized depending on the series of digits registered.
- 50 22. In a telephone system, a trunk having a plurality of normally disconnected branches, a relay for each branch for connecting the same with said trunk line, registering means for registering digits in telephone numbers, means individual to said trunk for controlling the setting of said registering means, and means responsive to the registration of different series of digits for separately energizing said relays.
- 55 23. In a telephone system, a trunk line having a plurality of normally disconnected branches, means including registering mechanism for selecting one of said branches before any of them are connected, a line relay normally connected to the trunk for controlling said registering mechanism in accordance with a portion of the digits in a telephone number, and connecting means controlled by said registering mechanism for connecting the selected branch to said trunk line.
- 60 24. In a telephone system, a trunk line having a plurality of normally disconnected branches, means including registering mechanism for selecting one of said branches before any of them are connected, a line relay connected to the trunk for controlling said registering mechanism in accordance with a portion of the digits in a telephone number, means also controlled by said line relay for repeating impulses over a particular one of said branches while said registering mechanism is being operated, switches responsive to said impulses, means controlled by said

registering mechanism for connecting the selected branch to the trunk line, and means for releasing said switches in case the branch selected is not the one over which impulses 5 were transmitted.

25. A universal switcher comprising a register, a plurality of hunting switches, a line relay for controlling said register, means responsive to the initial energization of said 10 line relay for operating one of said switches, and means responsive to the registration of a plurality of digits for operating one of the other switches and for releasing the first operated switch.

15 26. A universal switcher comprising a register, a plurality of hunting switches, a line relay for operating said register in accordance with a plurality of digits in a telephone number, and means responsive to the 20 registration of a plurality of digits for operating a particular one of said switches, the switch operated depending on the digits registered.

25 27. A universal switcher comprising a digit register, a plurality of hunting switches, means for operating and releasing said register a plurality of times, a device for storing the registered digits, and means controlled by said storage device responsive to the registration of a particular series of 30 digits for operating a particular one of said switches.

35 28. A universal switcher comprising a register switch operable in accordance with a plurality of different series of impulses, a plurality of hunting switches corresponding to said series of impulses, respectively, means controlled by said register switch for storing any series of digits registered, and means controlled by said storage means for operating the particular one of said hunting switches which corresponds to the registered 40 series of digits.

45 29. In a telephone system, a trunk line having a plurality of normally disconnected branches, each associated with a different exchange, a registering device individual to said trunk line for registering the digits in the exchange designations of called lines, 50 the said branches being maintained disconnected while such digits are being registered, and means responsive to the registration of the last digit in any exchange designation for connecting up the particular branch 55 which is associated with the exchange corresponding to the registered digits.

60 30. In a telephone system, a trunk line having a plurality of normally disconnected branches, each associated with a different exchange, a registering device, means individual to said trunk line for controlling the setting of said device to register the digits in the exchange designations of called lines, the 65 said branches being maintained disconnected while such digits are being registered, indi-

vidual relays for connecting said branches to the trunk line, and means responsive to the complete registration of any exchange designation for operating the proper relay to connect up the branch associated with the 70 exchange which corresponds to the registered exchange designation.

31. In a telephone system, a trunk line having a plurality of normally disconnected branches, a plurality of individual relays for 75 connecting said branches to the trunk line, a register switch responsive to a plurality of series of impulses received over said trunk line, a set of storage relays set by said register switch in accordance with the impulses 80 received, and circuits for said branch connecting relays controlled by said storage relays.

32. In a telephone system, a trunk line comprising two normally disconnected sections, a line relay connected to the first section for responding to digits in a telephone number, means controlled by said line relay for repeating such digits over the second section of said trunk line, means controlled 90 by said line relay for registering such digits, and means controlled by the registering means for connecting the two sections of said trunk line after a portion only of the digits in a number have been received so that the 95 remaining digits in the number are transmitted directly to the second section over the first.

33. In a telephone system, a main exchange, two branch exchanges, a trunk line 100 at the first branch exchange having three normally disconnected branches, one for handling local calls, one for handling calls to the main exchange, and the other for handling calls to the other branch exchange, means associated with said trunk line for registering sufficient of the digits in the number of a called line to determine in which exchange the line is located, and means controlled by said registering means as soon 105 as the location of the called line is determined for connecting up the correct branch to trunk the calling line to the desired exchange.

34. In a telephone trunking system, two 110 universal switchers, each comprising means for trunking a call over two different paths simultaneously, and a trunk line accessible in common to both said switchers as one of the paths over which calls are trunked.

35. In a telephone trunking system, means 115 for extending connections to called subscribers' lines comprising a first selector, two second selectors accessible to said first selector from different levels thereof, and a trunk line accessible in common to both said second selectors.

36. In a telephone trunking system, a first selector, two second selectors accessible 120 to said first selector from different levels 130

thereof, a hunting switch accessible to one of said second selector's but not to the other, a second hunting switch accessible to the other second selector but not to the first, and a trunk line accessible in common to both of said hunting switches.

37. In a telephone system, a trunk line having a plurality of normally disconnected branches, a branch connecting relay for each branch, a register switch at the junction of said branches, and permanent conductive connections between said relays and contacts in the bank of said register switch.

38. In a telephone system, a trunk line having a plurality of normally disconnected branches, a branch connecting relay for each branch, a register switch at the junction of said branches, storage relays controlled by said register switch, and conductors extending from said connecting relays to bank contacts of said register switch through contacts of said storage relays.

39. In a telephone system, two impulse repeaters for repeating digits in a telephone number, means for transmitting a series of impulses through said repeaters in tandem, and means responsive to a particular series of impulses for bypassing one of said repeaters so that the remaining series of impulses will go through the other repeater only.

40. In a telephone trunking system, a temporarily established connection including an impulse repeater, means for transmitting a plurality of series of impulses over said connection to a point beyond said repeater, and means for cutting out said repeater responsive to the first series of impulses provided such series has a particular value.

41. In a telephone trunking system, a temporarily established connection including an impulse repeater, means for transmitting a plurality of series of impulses over said connection to a point beyond said repeater, and means for cutting out said repeater responsive to the transmission of a part of said plurality of series of impulses provided the series constituting such part have particular values.

42. In a telephone trunking system, a tem-

porarily established connection including two serially related impulse repeaters, means for transmitting a plurality of series of impulses over said connection to a point beyond the second repeater, and means for cutting out the first repeater responsive to the transmission of the first series of impulses if such series has a particular value.

43. In a telephone trunking system, a temporarily established connection including two serially related impulse repeaters, means for transmitting a plurality of series of impulses over said connection to a point beyond the second repeater, and means for cutting out one of said repeaters responsive to the transmission of the first series of impulses if such series has a particular value.

44. In a telephone trunking system, a temporarily established connection including two serially related impulse repeaters, means for transmitting a plurality of series of impulses over said connection to a point beyond the second repeater, and means for cutting out one repeater responsive to the transmission of a part of said plurality of series provided the series constituting such part has particular values.

45. A switching device comprising a digit recording switch, and a plurality of trunk hunting switches individual thereto and separately operable thereby.

46. A switching device comprising a plurality of mechanically independent trunk hunting switches operable to further extend connections extended to said device, and a digit recorder individual thereto and arranged to determine in each of a plurality of cases which switch further extends a connection.

47. A switching device comprising a plurality of mechanically independent rotary switches, each rotatable in one direction only, and a digit registering device individual thereto and arranged to determine which rotary switch operates.

In witness whereof, I hereunto subscribe my name this 22d day of March, A. D. 1922.

ARTHUR BESSEY SMITH.
